LATCH LOCKING DEVICE

William J. Kerwin, Jr., Pawtucket, R. I.

Application October 20, 1932, Serial No. 638,698

15 Claims. (Cl. 70—91)

This invention relates to a door latch and lock for the same; and has for one of its objects to provide a lock for the latch bolt, which will be more secure than heretofore against opening the door by unauthorized persons.

Another object of the invention is the provision of a construction which will be so arranged that the possibility of rattle and noise from the construction will be eliminated or reduced to a minimum.

Another object of the invention is the provision of a construction in which the handle will be in a different position when locked than when unlocked, that one may observe whether the construction be in locked or in unlocked position, without manually trying the same.

A further object of the invention is the provision of a construction which when locked may be turned in a complete rotation in clockwise or counterclockwise direction when sufficient pressure is applied without affecting the latch bolt of the door and yet which will be sufficiently retarded in such movement by friction so as to cause the handle to remain in any position to which it has been forced.

With these and other objects in view, the invention consists of certain novel features of construction, as will be more fully described, and particularly pointed out in the appended claims.

In the accompanying drawings:

Fig. 1 is a front elevation of a bolt, door, escutcheon, handle and assembly of my lock therewith, shown in full lines in normal operating position and in dotted lines in the position to which it is placed for locking the same;

Fig. 2 is a section on line 2—2 of Fig. 1;

Fig. 3 is a section on line 3—3 of Fig. 1;

Fig. 4 is a section similar to Fig. 2, showing the construction in locked position with the handle in a vertical plane, as illustrated in dot-dash lines in Fig. 1;

Fig. 5 is a sectional view showing the manner of securing the escutcheon in position;

Fig. 6 is a section on line 6—6 of Fig. 5;

Fig. 7 is a sectional view showing the latch bolt and its operating plate thru which pressure is applied to move the bolt to retracted position; also showing the spring for forcing the bolt into operating position;

Fig. 8 is a perspective view of the handle;

Fig. 9 is a perspective view of the latch bolt operating member;

Fig. 10 is a perspective view of the bolt which is slidably mounted in the latch bolt operating member;

Fig. 11 is a perspective view of the sleeve member which fits within the hub of the handle;

Fig. 12 is a sectional view on the line 12—12 of Fig. 11;

Fig. 13 is a sectional view on the line 13—13 of Fig. 11;

Fig. 14 is a perspective view of the locking bolt for securing the hub of the handle and sleeve member together;

Figs. 15, 16, 17, 18 and 19 are sectional views showing various positions of the locking bolt and handle member, the sections being taken substantially on line a—a of Fig. 2;

Figs. 20, 21 and 22 are sectional views showing various positions of the pawl and the relation of the handle, the section being taken on substantially line b—b of Fig. 3.

Fig. 23 is a section looking in the opposite direction from that shown in Figures 15 to 21, inclusive, taken on line c—c of Fig. 4, but illustrating the locking bolt as in unlocked position and illustrating the projection on the handle hub and the slot in a portion of the sleeve member thru which it works;

Fig. 24 is a perspective view showing the two securing wedges as secured together.

It is customary in automotive manufacture to provide the lock for the door of an automobile in the handle, which is used for withdrawing the latch bolt from position. The handle of an automobile is usually of such construction that a length of gas pipe may be easily positioned over the handle to increase the leverage applied and this device has been frequently used by persons breaking into automobiles for twisting the handle from position and in the handles usually used with locks mounted in the hub of the handle the twisting off of the handle so destroys the lock as to permit an unauthorized person to enter the automobile so treated; and in order to prevent this, I have provided a construction which when locked will permit the handle to be forced thru a complete revolution in either direction without injury to the lock or the breaking thereof; and the following is a detailed description of the preferred embodiment of this invention illustrating the preferred means by which these advantageous results may be accomplished:

With reference to the drawings, 25 designates a portion of an automobile door having a latch bolt 26 which is secured to a plate 27 reciprocably mounted upon a pin 28 supported from the U-shaped frame 29.

This plate 27 and bolt 26 are forced in one direction by means of a coiled spring 30 and are 35

forced in the other direction by means of a U-shaped yoke 31 engaging the edge of the plate 27 at 32. This yoke has a pair of legs 34 and 36 connected by a bridge portion 33, its leg 36 is 5 rotatably supported in the portion 37 of the frame 29 which is forced inwardly, as illustrated. The leg 34 is provided with a bushing 34^a which is locked to the leg and is rotatably mounted in another portion of the U-shaped frame 29. This 10 bushing has a square hole 35 therein thru which the latch bolt operating member shown in Fig. 9 extends.

An escutcheon 38 is secured to the outer surface of the portion of the door 25 by means of pins 39 extending thru the surface plate 25 of the door and also thru the frame 29 where it is locked in place by means of wedges 40 extending thru openings 41 in the pins 39. These wedges may be connected together by a bridge piece 42, 20 as illustrated in modified view in Fig. 24. These wedges are also supported in the openings 43 in the frame, which maintain the wedges in place for securing the escutcheon in the desired position.

25 This escutcheon is provided with an internal bore 44 which is tapered as at 45, and in which there is positioned a sleeve member 46 which has a shell 47 secured at one end thereof provided with a tapered surface 48 to fit the taper 45 in the bore of the escutcheon. These tapered surfaces are forced into tight frictional engagement by means of a spring 49 engaging the end 50 of this shell and acting between it and a retaining plate 51 which is suitably held in the escutcheon 30 such as by means of fingers 52 extending over the outer surface thereof. This frictional engagement prevents this sleeve from rotating relative to the handle as later described.

35 A handle 53 is provided with a hub portion 54 which is shaped, as illustrated in Fig. 8, to provide a shoulder 59 by means of a reduced portion 57 having a projection 55 extending therefrom and a recess or slot 56 therein. This hub has a bore 58 extending therethrough to receive and bear upon the sleeve 46 and is freely rotatable 40 thereabout. The shoulder 59 abuts against the end of the escutcheon 60, and the reduced portion 57 extends inwardly from the end of the escutcheon and encircles the sleeve 48 while the projection 55 extends thru a slot 61 in the shell 47 mounted on the end of the sleeve member 46 for operation of the latch bolt, as will be presently described. The handle is prevented from moving axially with reference to the sleeve 46 45 by reason of the locking wire 62 which is inserted thru an opening 63 in the hub of the handle to seat within the half rounded registering grooves 64 in the hub of the handle and 65 in the outer surface of the sleeve 46.

50 The latch bolt operating member 66, as shown more particularly in Fig. 9, has a square end 67 engaging the square opening 35 in the bushing 34^a, while its inner larger end 68 is cylindrical in form and provided with a dove-tailed slot 69 in which there is mounted a pawl 70 having a tooth 71 extending therefrom and with a slot 72 provided therein. The latch bolt operating member is rotatably supported by the reduced circular portion 73 thereof bearing in the opening 74 in the retaining plate 51. A pawl 70 in its normal operating position is located in the slot 69 in such a position as to be engaged by the projection 55 of the hub of the handle so that as the handle is turned the latch bolt will be withdrawn thru the mechanism above described. The pawl 70

5 is of dovetailed formation corresponding with the shape of the slot 69 for the convenience of assembly of the parts in positioning the latch bolt operating member in its desired position in the escutcheon.

The sleeve member 46 is provided with a pin 75 which extends into the slot 72 of the pawl and is located at one side of the central axis of rotation of the sleeve 46. This sleeve 46 is also provided with a laterally extending opening 76 in which there is located a lock bolt 77 which may extend outwardly into the recess 56 in the hub of the handle when this recess is in registry with the slot 76 in the sleeve. The sleeve 46 is also provided with a bore 78 connecting with the 10 opening 76 and a larger bore 79 communicating therewith in which there is located a lock plug 80, which has an off center protuberance 81. Connection is had between the lock plug and lock bolt by an adapter 82 provided with an offset 15 pin 83 to fit within a slot 84 in the lock bolt 77 so that by turning the lock plug 80 the locking bolt may be moved thru the adapter into position to lock the hub and sleeve together or may be retracted by turning in the opposite direction 20 to prevent relative rotation of the hub and sleeve. 25

The adapter merely serves as a means for causing movement of the lock plug to be transmitted to the bolt and may be of different shapes for permitting lock plugs of different varieties to be used 30 in connection with the movement of the bolt of this invention to control its position. A spring 84 may be used to prevent rattle or undue movement of the adapter.

35 The lock plug 80 is held in the bore 79 by means of a spring pressed retaining member 85 fitting within the slot 86 in the bore 79 of sleeve 46. The flange 87 of the key plug fits flush with the end 88 of the handle by reason of the stepped relation 89 in the bore of the handle to receive a correspondingly shaped step 90 in the end of the sleeve 46, by which arrangement the lock fits flush with the outer end of the handle to prevent tampering with the same by unauthorized persons. The handle is maintained in the desired 40 working position against rotation by reason of a recess 91 therein in which there is a pin 92 forced outwardly by a spring 93, which pin fits within the notch 94 in the escutcheon to be under tension against rotation when in the position usual 45 for driving.

Operation

50 In operation, Fig. 15 illustrates the position of the handle, as shown in full lines in Fig. 1, in which position the locking bolt 77 is in unlocked 55 position, as illustrated in Fig. 15 and the pawl 70 is in a position to be engaged by the projection 55 so that rotating the handle by forcing its free end down, as illustrated by the arrow in Fig. 20, causes the latch bolt operating member 66 to be 60 rotated, the U-shaped yoke 33 operated, and the plate 27 and the latch bolt 26 withdrawn.

65 If it is desired to lock the door against unauthorized entry, the handle 53 will be raised to a predetermined position which I have here shown in vertical position with the projection 55 against the end of the slot 61 in the shell 47, in which position the recess 56 and the slot 76 will be in registry and movement of the barrel lock will cause the locking bolt thru the adapter to be 70 moved into the recess 56, as shown in Fig. 17, so that the hub of the handle and the sleeve 46 will be locked together to rotate as a unit in either direction. Fig. 18 illustrates the handle as 75

5 moved from the locked position as will be noticed by the slot 55, which is positioned in the shell 47 for assembly purposes, as having been moved from its uppermost position, as illustrated in
 10 Figs. 15, 16 and 17. In this position in which the handle and sleeve are locked together, the handle will have been moved back thru 90° so that its portion 55 will be out of contact with the pawl 70 and by reason of this relation when
 15 the handle is again rotated in a clockwise direction, as illustrated in Figs. 19 and 21, the pin 73 in the slot 72 because of its eccentric position, will cause the tooth 71 of the pawl 72 to be withdrawn from the path of movement of the projection 55 so that when the handle reaches the operative position or in a horizontal plane the projection 55 will pass the tooth of the pawl and may continue to rotate without turning the latch bolt operating member 68 and consequently will have no effect thereon. This same relation would occur regardless of whether the handle were moved in clockwise or counterclockwise direction.

20 The movement of the handle when in locked position causes the tapered surface 48 of the shell and the tapered surface 45 in the escutcheon to move one relative to the other and by reason of the spring 49 and this long bearing surface considerable friction is interposed against the force required for this movement which and by reason 25 of this friction the handle will be maintained in any position to which it may be left when such force is no longer applied.

30 The advantageous arrangement of this construction enables the entire lock assembly and operating mechanism to be all assembled in the escutcheon as a unit and the escutcheon then placed into the door as the last part of the assembly and secured therein by the wedges heretofore described. By this means the lock handle and escutcheon need not be handled separately at the point of assembly of these parts in the door and no special tools are required for securing it in the door.

35 The foregoing description is directed solely towards the construction illustrated, but I desire it to be understood that I reserve the privilege of resorting to all the mechanical changes to which the device is susceptible, the invention being defined and limited only by the terms of the appended claims.

40 I claim:

45 1. In a locking device, means for reciprocating a latch bolt, an escutcheon, a sleeve having a shell mounted in said escutcheon, said shell having a slot therein, a handle having a projecting portion extending thru said slot and engaging a portion of said means for operating said latch bolt.

50 2. In combination, a latch bolt, mechanism thru which said latch bolt is moved, including a pawl, a handle having a hub, a portion of which engages said pawl to operate said latch bolt, a sleeve member for withdrawing said pawl from the path of movement of said hub portion, and means for locking said hub to said sleeve member in a certain position, whereby movement of said handle from said inoperative locked position will withdraw said pawl prior to the hub portion engaging therewith.

55 3. In combination, a latch bolt, mechanism thru which said latch bolt is moved, including a pawl, a handle having a hub, a portion of which engages said pawl to operate said latch bolt, a sleeve for withdrawing said pawl from the path of movement of said hub portion, and means for locking

60 said hub to said sleeve member in an inoperative position, whereby movement of said handle will withdraw said pawl prior to the hub portion engaging therewith.

65 4. In a locking device, means for reciprocating a latch bolt, said means including a movable member having an eccentrically mounted pin thereon, a handle, means for selectively connecting said handle and member, a rotatable member provided with a slot therein, a pawl in said slot movable by said eccentrically mounted pin upon rotation of said handle when connected to said movable member to be selectively positioned for engagement with a portion of said handle to rotate said rotatable member.

70 5. In a locking device, a first, second and third rotatable members, mechanism for connecting said members together, comprising a pin secured to the second member, a pawl engaged by said pin and movably mounted on the third member, said second member selectively moving said pawl by said pin in or out of engagement with the first member.

75 6. In a locking device, a handle member, a sleeve member and a latch bolt operating member, and means for selectively connecting the handle member to either of said other two members for rotation with said handle relative to the unconnected member.

80 7. In combination, a latch bolt, a latch bolt operating member connected to said latch bolt to withdraw said latch bolt, a pawl slidably mounted in said member, and having a slot therein, an escutcheon, a handle having a hub with a recess therein rotatably mounted in said escutcheon, a projection on said hub for engaging said pawl to cause withdrawal of said latch bolt, a sleeve member in said hub, a pin on said sleeve at one side of the rotating axis thereof extending into said slot in said pawl, a locking bolt in said sleeve and a lock plug in said sleeve to move said locking bolt into said recess in the hub when in registry therewith to secure the sleeve and hub together, said relative location of securing being such that movement of the handle when so secured to the sleeve will cause the pawl to be withdrawn by the handle from the path of movement of said projection on said hub, whereby said latch bolt operating member is unaffected.

85 8. In a locking device, an escutcheon having a bore provided with a tapered surface, a sleeve having a shell provided with a tapered surface, a handle, provided with a hub encasing said sleeve, means for selectively locking said hub to said sleeve, and yielding means for urging said tapered surfaces into frictional engagement to prevent free movement of the handle when said hub and sleeve are locked to rotate together.

90 9. In a locking device, means for reciprocating a latch bolt, said means including a pawl, an escutcheon, a sleeve having a shell mounted in said escutcheon, said shell having a slot therein, a handle having a projecting portion extending through said slot to engage said pawl for operating said latch bolt.

95 10. In a locking device, means for reciprocating a latch bolt, said means including a rotatable member having a pawl movably mounted thereon, an escutcheon, a sleeve having a shell mounted in said escutcheon, said shell having a slot therein, a handle having a projecting portion extending through said slot, to engage said pawl for rotating said rotatable member.

100 11. In a locking device, means for reciprocating a latch bolt comprising a rotatable member

having a pawl movably mounted thereon, an escutcheon, a sleeve mounted in said escutcheon, said sleeve being provided with a pin and a shell, said shell having a slot therein, a handle having a 5 projecting portion extending through said slot for engaging said pawl, said pawl being movable by said pin.

12. In a locking device, a rotatable member for actuating a latch bolt, a pawl movably connected 10 to said member, a rotatable handle, an element connected with said handle adapted to operatively engage said pawl, a lock device, and means for moving said pawl upon rotation of said handle preventing engagement of said pawl and said element upon locking of said lock device.

13. In a locking handle arrangement, a rotatable member for actuating a latch bolt, a rotatable handle having an engaging element, a movable engaging element on said rotatable member, 15 means controlling the movement of said movable element to normally position said movable element in the path of the handle element, and means locking the handle to said positioning 20

means for simultaneous movement for moving the movable element out of the path of the handle element.

14. In a locking device, a rotatable element, two additional rotatable elements, one of said additional elements being operatively connected to a latch mechanism, and lock means manually operable to selectively connect said first rotatable element with either of said additional rotatable elements. 5

15. In a locking handle arrangement, a rotatable member for actuating a latch bolt, a rotatable handle, elements respectively connected to said handle and said member and adapted to operatively engage upon rotation of said handle, said 10 member element being slidable, a lock device, means for sliding said slidable element in engaging position upon movement of said handle when said lock device is unlocked, and means for sliding the slidable element to non-engaging position upon movement of said handle when said lock device is locked. 15

WILLIAM J. KERWIN, JR. 20
